UNITED STATES PATENT OFFICE.

RAPHAEL EDGAR DU BE, OF DENVER, COLORADO.

GAS ENGINE.

Application filed April 8, 1925. Serial No. 21,648.

To all whom it may concern:

Be it known that I, RAPHAEL EDGAR DU BE, a citizen of the United States, and a resident of Denver, in the county of Denver and State of Colorado, have invented certain new and useful Improvements in Gas Engines, of which the following is a specification.

This invention relates to an internal combustion engine of the horizontal type and has for its object the provision of an engine having opposed pistons working in a single cylinder with the combustion chamber being located between the pistons so that the expansion stroke will be simultaneous for both pistons to drive said pistons in opposite directions and rotate a single crank shaft.

Another object of the invention is the provision of an engine having a combustion chamber between a pair of opposed pistons which through rock levers and links operate a single crank shaft located directly below the combustion chamber and at right angles to the axis of the single cylinder for the pistons.

A further object of the invention is the provision of an engine having a single cylinder and opposed pistons, with the combustion chamber disposed between the pistons so that an explosive charge will drive both pistons for rotating a single crank shaft thereby providing for a saving in fuel with greater power.

A still further object of the invention is the provision of an engine having opposed pistons acted upon at each expansion stroke for driving a single shaft and in which rock levers are provided for transmitting the power stroke to the crank shaft, the levers having their arms offset in such a manner that a minimum of space is required to house the engine.

This invention will be best understood from a consideration of the following detailed description, in view of the accompanying drawing forming a part of the specification; nevertheless it is to be understood that the invention is not confined to the disclosure, being susceptible of such changes and modifications which shall define no material departure from the salient features of the invention as expressed in the appended claims.

In the drawings,

Figure 1 is a longitudinal vertical section of the engine.

Figure 2 is a vertical section of the engine taken along the line 2-2 of Fig. 1.

Figure 3 is a view in perspective of a rock lever mounted at each end of the engine.

Figure 4 is a view in perspective of the crank shaft.

Figure 5 is a perspective view of the cam shaft.

Referring more particularly to the drawings a frame is shown for supporting a horizontal cylinder 1. The frame may be cast integrally with the cylinder or made separately and the cylinder bolted to the frame. The frame consists of pairs of end standards 2 and 3 provided each with a bracket 4 having bearings 5 to support a rock shaft 6 or 7.

Integrally formed with the standards at their lower ends are a pair of arcuately shaped beams 8 having bearings 9 intermediate their ends. The bearings are split as is usual in order that a crank shaft 10 mounted therein may be removed when desired. Bolts 11 are provided for fastening the upper section of the bearing and for adjusting said section relative to the lower section.

The upper ends of the standards 2 and 3 are connected by transverse bars 12 curved to conform to the curvature of the cylinder 1 to receive said cylinder adjacent its ends. Transverse bars 13 connect the lower ends of the standards together.

A piston rod 14 is connected at one end to a wrist pin 15 carried by a reciprocating piston 16 mounted in one end of the cylinder, the other end of the rod being provided with a fork 17 pivoted at 18 to the upper arm 19 of a rock lever 20. The rock lever has a journal 21 carried by the rock shaft 6. The lower arm 22 of said lever is pivotally connected at 23 to a fork 24 at one end of a link 25, the other end of the link being connected to a crank 26 on the crank shaft 10.

A rod 27 connected at one end to a wrist pin 28 carried by a piston 29 opposed to the piston 16 is provided with a yoke 30 at its other end which is pivoted at 31 to the upper end of an arm 32 of a rock lever 33. The rock lever has a journal 34 mounted on the rock shaft 7. The lower arm 35 of said lever is pivoted at 36 in a yoke at one end of a link 38. This link like the link 25 extends inwardly but in a different plane from

link 25 and is connected to a crank 39 set at an angle to crank 26 so that at no time will there be a dead center for the engine; thus the resistance due to carrying the 5 tons off dead center will be entirely eliminated.

A combustion chamber 40 is located in the cylinder 1 between the heads 41 and 42 of the respective pistons 16 and 29 and during 10 the expansion stroke is increased in size by the receding pistons.

The portion of the cylinder above the combustion chamber 40 is provided with a hollow boss 43 in communication with the combustion chamber by a passage 44. The boss has a head or closure 45 in which are mounted the exhaust and intake valves 46 and 47 respectively. The intake valve engages a seat 48 forming an intake port of the passage 49 in the head 45 of said boss. A spring 50 engaged at one end by a bearing 51 on a stem 52 and at its other end by the head 45 maintains the intake valve on its seat.

A spring 53 on a stem 54 of the exhaust 25 valve 46 retains said valve on a seat 55 forming an exhaust port at the inner end of the exhaust passage 56. The spring 53 like the spring 50 engages a bearing 57 at one end on the stem 54, and at its other end the head 45 30 of the boss 43.

A spark plug 58 is screwed into a threaded opening in the head 45 of said boss and is electrically connected in the usual manner with an ignition system (not shown).

35 The intake valve 47 is operated through a tappet 59 pivoted at 60 to a bracket 61 rising from the head 45 of the boss. A tappet 62 actuates the valve 46 and is likewise pivoted on the pin 60 carried by the 40 bracket 61. A link 63 is pivoted at its upper end to the tappet while a link 64 is pivoted at its upper end to the tappet 62.

A gear 65 on the crank shaft 10 drives a gear 66 on a cam shaft 67 mounted in bearings 68 supported by the frame. A cam 69 on shaft 67 engages the rod or link 64 for reciprocating the same to actuate the exhaust valve 46 while a cam 70 causes reciprocation of the rod or link 63 for actuating the 50 intake valve 47.

It will be noted that the rods 63 and 64 are on opposite sides of the cylinder and mounted in bearing for vertical sliding movement.

55 Any number of cylinders may be placed alongside of each other and their pistons so cooperatively related in positions that certain of the pistons may be on their compression stroke while others may be completing 60 their expansion stroke. It will be appreciated that the strokes of the piston will be determined by the angular setting of their respective cranks on the crank shaft.

The operation of my device is as follows:

65 The crank shaft 10 is revolved in any ap-

proved manner causing reciprocation of the pistons 16 and 29 toward and away from each other providing suction and compression strokes. At the proper point in the cycle the compressed combustible mixture 70 drawn in through the intake passage 49 and past the open intake valve 47 is ignited in the reduced combustion chamber 40 between the opposing pistons 16 and 29 and the expansion of the gases forces the pistons 75 apart rocking simultaneously but in opposite directions, the levers 19 and 32 through the respective piston rods 14 and 27. The links 25 and 38 are moved inwardly and outwardly driving the crank shaft 10, both 80 links pushing or pulling in a coordinate manner. The angular setting of the cranks, that is one crank disposed slightly above the horizontal and the other crank slightly below said horizontal. By both pistons being operated simultaneously in opposite directions by the same explosive charge, not only a great economy in fuel is had but greater power output results since both pistons are driven with equal force to revolve the crank shaft.

The gears 65 and 66 are so timed and the cams 69 and 70 so placed that the exhaust and intake valves will be properly actuated during the respective exhaust and suction 95 strokes for the proper operation of the engine.

The opposite arms of the rock levers 20 and 33 are offset from each other so that not only a compact and efficient engine is had 100 but the links 25 and 38 may be placed in close associations for restricting the width of the device. Furthermore the disposition of the rock levers at the ends of the frame provides for a large leverage in operating 105 the cranks of the crank shaft and a smoother running engine.

A casing 75 completely encloses the frame, rock levers and crank shaft. The casing may be made in sections so that the sections 110 may be readily removed for inspection and repairs. Cover plates 76 are removably connected to the upper edges of the casing and curved at its inner ends as shown at 77 to 115 conform to the curvature of the cylinder and secured to said cylinder at these points.

A water jacket 78 embraces the cylinder adjacent the combustion chamber and is connected to the usual cooling system for the purpose. Since the cooling system forms 120 no part of the present invention the same has been omitted.

The casing 75 is supplied with lubricating oil at a predetermined level and the oil 125 is carried to all the moving parts in the usual manner. The level of the oil in said casing may be such that the crank shaft and gears 65 and 66 may be directly supplied with lubrication by the splash system.

By the construction of the two pistons 130

moving towards each other in a single cylinder mechanism, a decreasing compression chamber being progressively affected, a higher compression is obtained than when 5 a single piston is employed in a cylinder.

I claim:

1. In an internal combustion engine, a horizontal cylinder, opposed pistons mounted in said cylinder, a frame supporting the cylinder, a rock lever mounted at each end of the frame, the upper arm on each lever being offset from the lower, the corresponding arms of the levers being located in different vertical planes, a shaft provided with 10 a plurality of cranks, a rod connecting a crank with a lower arm of a rock lever, a piston rod connecting the upper arm of each rod with a piston, a casing enclosing the frame, crank shaft, and cover plates 15 conforming to the curvature of the cylinder and connected to said cylinder and casing.
2. In an internal combustion engine a horizontal cylinder, a frame supporting said cylinder and comprising a pair of longitudinal and arcuately shaped beams, a pair of standards rising from the opposite ends of said beams, a plate connecting a pair of the standards at the ends of the frame and curved to conform to the curvature of the 20 cylinder for receiving said cylinder, brackets extending outwardly from the standards, a shaft mounted in each pair of brackets, a rock lever carried by each shaft, pistons in the cylinder, means connecting a piston with a lever, a crank shaft and 25 means connecting each lever with the crank shaft whereby said shaft is revolved.
3. In an internal combustion engine a horizontal cylinder, a frame supporting said cylinder and comprising a pair of longitudinal and arcuately shaped beams, a pair of standards rising from the opposite ends of said beams, a plate connecting a pair of the standards at the ends of the frame and curved to conform to the curvature of the 30 cylinder for receiving said cylinder, brackets extending outwardly from the standards, a shaft mounted in each pair of brackets, a rock lever carried by each shaft, pistons in the cylinder, means connecting a piston with a lever, a crank shaft and 35 means connecting each lever with the crank shaft whereby said shaft is revolved, a housing enclosing said frame, crank shaft and rock levers, and a removable cover plate connected to each 40 end of the cylinder and the housing.

RAPHAEL EDGAR DU BE.
